John O. BETZ
BY *W. M. Stoddard*
ATTORNEY.

UNITED STATES PATENT OFFICE

JOHN O. BETZ, OF ADRIAN, MICHIGAN

PAPER BOX

Application filed March 12, 1930. Serial No. 435,086.

My invention relates to receptacles for delivered packages and a special object of my improvements is to provide a receptacle for periodicals or mail in rural free delivery. For this particular use it is desirable to have a receptacle in which the package can be readily placed without stopping and in which it will be protected from the weather and rain. I have accomplished this object by the construction shown in the accompanying drawings, in which:

Figure 1 is a perspective view of an apparatus embodying my invention and the upper part of the standard upon which it is supported.

Figure 2 is a section on the line II, II, Figure 1, looking in the direction of the arrows.

Figure 3 is a detail section on the line III, III, Figure 2.

2 is an upright standard upon which the receptacle embodying my invention is secured.

Said receptacle is made up of two parts. The part 3 is in the shape of a rectangular box having the bottom 3a resting upon the top of the standard 2 and extending outward and curved downward in the leaf 3a2 and having its front and top opened and its ends closed by the usual end pieces 3b, 3b, and closed at the back by the wall 3c.

The part 4 is of a similar construction to the part 3, but complementary thereto. The front is open, the top 4a extends forward and curves upward in the leaf 4a2. There are end pieces 4b, 4b which fit against and outside of the end pieces 3b, 3b, and there is a back 4c. The part 4 is hinged to the part 3 by pivots 34 in the lower left hand corner of the end pieces 3b, and 4b.

The messenger or postman may drive past this receptacle and thrust the mail in through the open front. If it is not accurately placed it will be guided to position by the leaves 3a2, 4a2, and the part 4 may rise to accommodate the size of the package, or if the delivery is made at too high a point so as to prevent the bundle of mail entering the receptacle in the usual way the part 4 will rise, yielding to the impact of the package turning about its hinge and guiding the package to its place.

The end pieces 4b fitting down beside the end pieces 3b prevent the entrance of any water and the leaf 4a2 turning upward and extending to the front shields the open front of the receptacle. All exposed edges are corrugated so that they will not cut the hands that may accidentally strike against them.

What I claim is:

1. A receptacle for mail consisting of two parts hinged together so that the upper part 60 may turn about a horizontal axis at its rear edge and forming an enclosure with its front portion open, the upper part being provided with a leaf 4a2 extending forward and upward over the open front and the lower portion having a leaf extending forward and downward below the open front.

2. A receptacle for mail consisting of two parts hinged together so that the upper part 70 may turn about a horizontal axis at its rear edge and forming an enclosure with its front portion open, the upper part being provided with a leaf 4a2 extending forward and upward over the open front and provided with side pieces adapted to fit against the side 75 pieces of the lower part, for the purpose described.

In testimony whereof, I sign this specification.
